SOUND TAPE SPOOL HOLDER

Gerhard Dietrich, Furth, Bavaria, Germany, assignor to
Max Grundig, Furth, Germany

Filed Oct. 15, 1965, Ser. No. 87,493

Term of patent 14 years

Claims priority, application Germany July 8, 1965

(Cl. D26—14)

Fig. 3.

Fig. 1.

Fig. 2.

Fig. 4.

FIGURE 1 is a side view of a spool holder embodying my new design, the opposite face being substantially identical with FIGURE 1;

FIGURE 2 is an end view of FIGURE 1, the opposite end view being substantially identical with FIGURE 2;

FIGURES 3 is a view of the edge of FIGURE 1 as seen above FIGURE 1; and

FIGURE 4 is a view of the lower edge of the holder as seen from the lower side of FIGURE 1.

The broken line showing of magnetic tape in FIG. 4 is for illustrative purposes only.

I claim:

The ornamental design for a sound tape spool holder, as shown and described.
